HIGH TEMPERATURE HIGH PRESSURE APPARATUS

Robert H. Wentorf, Jr., Schenectady, N.Y., assignor to General Electric Company, a corporation of New York

Filed Sept. 30, 1955, Ser. No. 537,630

4 Claims. (Cl. 18—16.5)

My invention relates to high temperature high pressure apparatus and specifically to such apparatus in which high temperatures and high pressures are maintained for prolonged periods of time.

In a copending application of Francis P. Bundy, Serial No. 488,042, filed February 14, 1955 and assigned to the same assignee as the present application, an apparatus is described to effect and control reactions occurring at temperatures of the order of several thousand degrees centigrade and pressures of the order of 20,000 to 40,000 atmospheres for long time intervals. Such apparatus comprises a reaction vessel which is positioned between a pair of opposed, recessed dies to provide a specimen chamber to be subjected to temperatures and pressures of the order mentioned.

A high temperature high pressure apparatus which provides a reaction vessel of increased size is desirable to accommodate larger amounts of materials to be heated and pressed. In previous devices, reaction vessel size was limited by thickness of the surrounding insulating and pressure resisting gasket. Such a gasket could be increased in size to enlarge the vessel but application of high pressure caused the gasket to extrude laterally from between opposed members with attendant loss of pressure in the reaction vessel. The invention of the present application provides an apparatus which eliminates the previous gasket assembly and produces an increase in reaction vessel size.

Accordingly, it is an object of the invention to provide a new and improved high temperature high pressure apparatus.

It is another object of the invention to provide an improved high temperature high pressure apparatus which increases the size of the reaction vessel.

It is a further object of the invention to provide an improved high temperature high pressure apparatus which effects and controls reactions at temperatures of over one thousand degrees centigrade and pressures of over 40,000 atmospheres.

In carrying out my invention in one form, a reaction vessel is positioned within a pair of inner pressure resisting members and outer electrical and thermal insulating members between a pair of opposed, recessed dies to provide an enlarged specimen chamber which is subjected to high temperature and high pressure conditions.

These and various other objects, features, and advantages of the invention will be better understood from the following description taken in connection with the accompanying drawing in which:

Fig. 1 is a front elevational view of a hydraulic press with a high temperature high pressure apparatus which embodies my invention; and

Fig. 2 is an enlarged sectional view of the high temperature high pressure apparatus which is shown in Fig. 1.

In Fig. 1 of the drawing, a hydraulic press comprises a base 10 with a press bed 11 on which is mounted a

2

plurality of vertical shafts 12 to support a carriage 13. A ram 14 is mounted on the undersurface of carriage 13 to be actuated by an associated hydraulic piston 15 while a platen 16 is positioned centrally on press bed 11 in axial alignment with ram 14. Both ram 14 and platen 16 are recessed to partially position members 17 therein, each of which comprises a central die 18 with surrounding binding rings 19. An annular conducting ring 20 with a connector 21 is positioned around the periphery of each outer binding ring to supply electric current from a source of power (not shown) through rings 19 and dies 18 to a high temperature high pressure reaction vessel which is described below. A layer of electrical insulation 22 is preferably provided between at least one member 17 and its associated platen 16 to prevent conduction of electric current through the press. If it is desired, conducting rings 20 can be connected to ram 14 and platen 16 to reduce the length of members 17.

As is best shown in Fig. 2, the opposed or outer faces of dies 18 are recessed to provide a frusto-conical cavity 23 with an electrical and thermal insulating frusto-conical gasket 24 in contact therewith. Pressure resisting frusto-conical members 25 are positioned concentrically with and adjacent insulating gaskets 24 within cavity 23 of each die, and are positioned to project from the cavities 23 to provide outer abutting faces. The outer faces of opposed pressure resisting members 25 have an annular gasket or layer of electrical insulation 26 therebetween to prevent short-circuiting of the current path. Pressure resisting members 25 define a central aperture 27 which extends between opposed dies. While an electrically conductive object or specimen can be placed in aperture 27 to be subjected to high temperature high pressure conditions, I prefer to employ a reaction vessel 28 within aperture 27 which vessel is in electrical contact with dies 18. Vessel 28 comprises a pair of spaced conductive discs 29 with a hollow conductive tube 30 therebetween adapted to contain a specimen 31 to be subjected to high temperature high pressure conditions. A hollow cylinder 32 of electrically insulating material is positioned around and engaging tube 30 between and in contact with discs 29 to complete the assembly of reaction vessel 28. If it is desired, reaction vessel 28 may be in the form of a hollow casing which is in electrical contact with dies 18. A cap 33 is positioned between each die 18 and its associated disc 29 to provide a thermal insulating core 34 with a surrounding outer conductive rim 35 in electrical contact with the die. Examples of suitable materials from which members 23, cylinder 32 and cores 34 can be made are pyrophyllite and catlinite.

In the operation of the high temperature high pressure apparatus shown in Figs. 1 and 2, each member 17 with associated conducting ring 18 and connector 19 is positioned partially within the recess of its associated ram 14 and platen 16 in the press. Specimen 31, which is to be subjected to a high temperature high pressure environment, is placed in tube 30 within cylinder 32 between discs 29 to complete reaction vessel 28. After a cap 33 is provided at each end of vessel 28, pressure resisting members 25 are placed around the vessel and cap 33 to enclose the structure. A layer of electrical insulation 26 is positioned between opposed or abutting faces of members 25 to prevent conduction of electrical current therebetween. Electrical and thermal insulating members 24 surround members 25 to provide an outer insulating layer. The assembly is then positioned within opposed frusto-conical cavities 23 of dies 18 to complete the high temperature high pressure apparatus. Pressure which is supplied by piston 15 through its associated ram 14 and member 17 is applied to specimen 31 by opposed dies 18. At the same time, electric current is supplied from one electrical connector, such as, upper

connector 21 to upper conducting ring 20, binding rings 19, dies 18, rim 35, and disc 29 to generate heat in tube 30 of vessel 28. The current path continues through lower disc 29, rim 35, dies 18, binding rings 19, conducting ring 20 and connector 21 to the electrical source. Pressures in excess of 40,000 atmospheres and temperatures higher than 1,000° C. have been maintained in such apparatus for periods of hours. If it is desired, reaction vessel 28 may also be subjected to high pressures alone.

As will be apparent to those skilled in the art, the objects of my invention are attained by the use of a reaction vessel which is positioned within a pair of inner pressure resisting members and outer electrical and thermal insulating members between a pair of opposed, recessed dies to provide an enlarged specimen chamber to be subjected to high temperature and high pressure conditions.

While other modifications of this invention and variations of apparatus have not been described, the invention is intended to include all such as may be embraced within the following claims.

What I claim as new and desire to secure by Letters Patent of the United States is:

1. High temperature high pressure apparatus comprising a pair of opposed dies, means for exerting pressure against at least one of said dies, a layer of insulation between one of said dies and its associated pressure means, an electrical connection to each of said dies, the opposed outer faces of said dies being recessed to provide a cavity therein, an electrical and thermal insulating gasket in contact with the wall of each of said cavities, a pressure resisting member concentrically with and adjacent each said insulating gasket and projecting from said cavities to provide abutting faces, said pressure resisting members forming a central aperture between said dies adapted to contain an object to be subjected to high temperature high pressure conditions, and a layer of insulation between adjacent abutting faces of said pressure resisting members.

2. High temperature high pressure apparatus comprising a pair of opposed members, means for exerting pressure against at least one of said members, a layer of insulation between one of said members and its associated pressure means, an electrical connection to each of said members, each member comprising a die, at least one binding ring around said die, the opposed faces of said dies being recessed to provide a conical cavity therein, an electrical and thermal insulating frusto-conical gasket in contact with the wall of each of said cavities, a pressure resisting frusto-conical member concentric with and adjacent said insulating gasket, and projecting from said cavities to provide abutting faces, said pressure resisting members forming a central aperture between said dies adapted to contain a specimen to be subjected to high temperature high pressure conditions, and a layer of insulation between adjacent abutting faces of said pressure resisting members.

3. High temperature high pressure apparatus comprising a pair of opposed members, means for exerting pressure against at least one of said members, a layer of insulation between one of said members and its associated pressure means, an electrical connection to each of said

members, each member comprising a die, at least one binding ring around said die, each of the opposed outer faces of said dies being recessed to provide a frusto-conical cavity, an electrical and thermal insulating frusto-conical gasket for each cavity and in contact with the wall of its associated cavities, a pressure resisting frusto-conical member concentric with and adjacent each of said insulating gaskets, and projecting from said cavities to provide abutting faces, said pressure resisting members forming a central aperture, a reaction vessel located within said aperture adapted to contain a specimen to be subjected to high temperature high pressure conditions, said vessel being in electrical contact with said dies, and a layer of insulation between adjacent abutting faces of said pressure resisting members.

4. High temperature high pressure apparatus comprising a pair of opposed members, means for exerting pressure against at least one of said members, a layer of insulation between one of said members and its associated pressure means, an electrical connection to each of said members, each member comprising a die, at least one binding ring around said die, each of the opposed outer faces of said dies being recessed to provide a frusto-conical cavity, an electrical and thermal insulating frusto-conical gasket for each cavity and in contact with the wall of each of said cavities, a pressure resisting frusto-conical member positioned concentrically within and adjacent said insulating gaskets, and projecting from said cavities to provide abutting faces, a layer of insulation between adjacent abutting faces of said pressure resisting members, said pressure resisting members forming a central aperture, a reaction vessel located within said aperture, said vessel comprising a pair of spaced conductive discs, a hollow conductive tube adapted to contain a specimen to be subjected to high temperature high pressure conditions positioned between said discs, an electrical and thermal insulating cylinder around and engaging said tube and said discs, a cap adjacent the end of each of said discs, said cap comprising a heat insulating core, and an outer conductive rim surrounding said core, said rim being in electrical contact with its associated die.
